FUNCTIONAL BITE DENTAL TRAY

James W. Benfield, 60 Pinewood Road, Hartsdale, N.Y.

Filed May 20, 1964, Ser. No. 80,082

Term of patent 14 years

(Cl. D24—1)

FIG.-1

FIG.-2

FIG.-3

FIG.-4

FIG.-5

FIG. 1 is a top plan view of a functional bite dental tray showing my new design;

FIG. 2 is a sectional view along the center line II—II of the tray of FIG. 1;

FIG. 3 is a fragmentary isometric view as seen from the left of FIG. 1;

FIG. 4 is a sectional view along the line IV—IV of FIG. 2; and

FIG. 5 is a bottom plan view thereof.

I claim:

The ornamental design for a functional bite dental tray, as shown.
